[57] ABSTRACT

This invention provides a mobile integral drafting instrument comprising a straight edge having a first clutch mechanism to provide vertical movement thereof on a drawing media and a second clutch mechanism to provide a circular movement thereof for drawing free and predetermined angles, straight lines and curved lines without the aid of additional instruments.

DRAFTING INSTRUMENT

This invention relates to instruments in the mechanical and technical drafting field and more particularly to instruments for drawing angles, straight lines, and curves.

Heretofore in the field of mechanical or technical drafting, straight edges, protractors, rulers and other measuring devices, compasses, T-squares and triangles, either as separate elements or in conjunction with each other, were required in order to measure and/or draw straight lines, angles and curved lines. Of necessity, this required a number of separate drawing instruments to obtain a desired result.

The instant invention eliminates the necessity of protractors, compasses, T-squares, straight edges, triangles and rulers by providing an integral mechanical drafting instrument having a unique clutch mechanism which permits the performance of all of the foregoing functions.

The drawing instrument of the instant invention is comprised of a flat straight edge having predetermined measuring indicia thereon and a circular or semicircular portion also provided with predetermined measuring indicia. Associated with the flat edge portion of the instrument and the circular portion thereof are independent clutch mechanisms which, when selectively applied, will result in solely a vertical movement on a drawing media or a circular movement of the instrument upon the drawing media, as will hereinafter be more fully described. In addition, by concurrently activating both clutch mechanisms, a unique braking action is achieved which prohibits either vertical, horizontal or circular motion of the instrument.

This invention further provides a means to absorb and eliminate undesirable lateral or horizontal motion of the instrument.

It is therefore the object of this invention to provide a simple, mobile, integral mechanical drafting instrument for drawing straight lines, angles and curved lines without the use of extraneous instruments.

A further object is to provide a simple, mobile, integral mechanical drafting instrument which can be activated in a preselected vertical or circular track without the use of extraneous instruments.

Another object is to provide a simple, mobile, integral mechanical drafting instrument which is provided with a simple clutch means for selective movement of the instrument in a vertical or circular direction without the use of extraneous instruments.

Yet another object is to provide a simple, mobile, integral mechanical drafting instrument which has a simple unique braking mechanism to prohibit movement of the instrument in any direction without the use of extraneous instruments.

Yet a further object is to provide a simple, mobile, integral mechanical drafting instrument which is capable of drawing a plurality of predetermined parallel lines and a plurality of concentric circular lines without the use of extraneous instruments.

Other objects and advantages will be readily apparent from the following description taken in conjunction with the accompanying drawings, in which:

FIG. 1 is a top plan view of the instrument of the instant invention;

FIG. 2 is an elevational view of the right side of the instrument of FIG. 1 showing the actuating wheels in their inoperative positions;

FIG. 2A is an elevational view similar to FIG. 2 except that the actuating wheels are shown in their operative braking positions;

FIG. 3 is a front elevational view of the instrument of FIG. 1 illustrating the actuating wheels for providing vertical movement in their inoperative position;

FIG. 3A is an elevational view similar to FIG. 3 except that the actuating wheels and axle are illustrated in their operative position;

FIG. 4 is a cross-sectional view of the magnetic holder and retractor for the axle of the vertical movement actuating wheels taken on the line 4-4 of FIG. 3;

FIG. 4A is a view similar to FIG. 4 except taken on the line 4A-4A of FIG. 3A;

FIG. 5 is a front elevational view, partly sectioned of the instrument taken on the line 5-5 of FIG. 1 showing the actuating wheel for providing circular movement in its inoperative position;

FIG. 5A is a front elevational view, partly sectioned similar to FIG. 5 except that the actuating wheel and axle for circular movement are in their operative positions;

FIG. 6 is a cross-sectional view of the magnetic holder and retractor for the axle of the circular movement actuating wheel taken on the line 6-6 of FIG. 5;

FIG. 6A is a view similar to FIG. 6 except taken on the line 6A-6A of FIG. 5A;

FIG. 7 is a side elevational view of the vertical movement actuating wheels and axle; and

FIG. 8 is a side elevational view of the circular movement actuating wheel and axle;

Referring more particularly to FIG. 1, reference numeral 10 designates generally the integral drafting instrument of the instant invention having a flat, elongated, straight edge portion 10a provided with predetermined measuring indicia 11 along the edges thereof and a flat circular or semicircular portion 10b provided with predetermined measuring indicia 12 in a circular pattern thereon. Straight edge portion is also provided with openings 13 passing through the face thereof (as best seen in FIGS. 3 and 5).

A first clutch means positioned on straight edge portion 10a, said first clutch means comprised of actuating wheels 14 for providing vertical movement interconnected by elongated shaft or axle 15 which continues through said wheels 14 and are secured at each end by a housing guide 16. (See FIGS. 1, 3, 3A and 7). Axle 15 may be of any material which is susceptible to magnetic flux.

Housing guides 16 are provided with recesses for accommodating the ends of axle 15 so as to prohibit forward movement of the axle relative to the straight edge portion 10a yet allow limited axial and vertical movement thereof relative to housing guide 16.

Axle 15 passes through retraction and maintenance means 17 each of which includes a magnet 17a spatially positioned from the face of straight edge portion 10a. (As best seen in FIGS. 4 and 4A). By virtue of magnet 17a, retraction and maintenance means 17 serve to hold axle 15 elevated relative to the face of straight edge portion 10a, and concomitantly maintaining wheels 14, in disengaged relationship to the drawing

media. When a sufficient downward normal force is applied to axle 15 so as to overcome the magnetic force of magnet 17a on said axle, the axle is disengaged and normally downwardly displaced toward the straight edge portion 10a, and concomitantly the drawing media, so that wheels 14 pass through openings 13 and engage said drawing media.

It should be noted that although a pair of retraction and maintenance means 17 are herein disclosed, any number consistent with desired design may be utilized without departing from the scope of the invention herein. It should be further noted that although the retraction and maintenance means 17 herein disclosed utilize a magnet 17a in conjunction with an axle 15 composed of material susceptible to magnetic flux, spring means and the like may be utilized in said retraction and maintenance means without departing from the scope of the invention herein. However, it should be noted that the use of magnetic retraction and maintenance means is preferable since an application of force against a resistant spring means may transmit said force to the straight edge portion 10a of the instrument and concomitantly to the drawing media, thereby creating a friction between said drawing media and the said straight edge portion.

A contact bar 18 engages axle 15 and is carried thereby so as to be free from contact with the face of straight edge portion 10a. Although a number of conventional means may be utilized to attach said contact bar 18 to the axle 15, as disclosed herein said contact bar is tubular and is provided with an axial split separating the wall member thereof so that the same may be snapped onto axle 15. Thus contact bar 18 is engaged about axle 15, yet suspended away from surface of straight edge portion 10a.

Upon the application of a normal force to contact bar 18 said normal force is transmitted to axle 15 causing said axle to flex downwardly and subsequently disengage from magnet 17a of retraction and maintenance means 17. Thus wheels 14 are caused to engage the drawing media so that upon the application of an additional vertical force along the plane of the drawing media (as designated by arrow A in FIG. 1) the instrument of the instant invention will travel in that predetermined direction. It should be noted that at no time, whether or not an actual force is applied to contact bar 18, said contact bar does not contact the surface of straight edge portion 10a. Thus, none of the normal force is transmitted to the face of straight edge portion 10a and press said straight edge portion against the drawing media to cause detrimental frictional resistance during the vertical travel of the instrument.

Upon the release of the aforementioned axial force to contact bar 18, the magnetic force of magnets 17a retract axle 15 in the reverse normal direction thereby lifting wheels 14 from engagement with the drawing media.

To avoid lateral movement due to the transient forces on the instrument while a simultaneous normal and forward force is being applied to contact bar 18, a helical compression spring means 19 which encompasses axle 15 is positioned between one of the wheels 14 and the nearest housing guide 16 adjacent thereto. It is important to note that only one spring means is utilized since if an additional spring were inserted between the opposite wheel 14 and adjacent housing guide 16, the additional spring means would be coun-

ter-productive to the first mentioned spring means and equalize or eliminate the effectiveness of the first mentioned spring means.

Associated with the circular or semi-circular portion 10b of the drafting instrument herein is a second separate clutch means consisting of an actuating wheel 20 for providing circular movement of the drafting instrument in the direction indicated by arrow B in FIG. 1 (See FIGS. 1, 5 and 5A). Said second clutch means is further comprised of a spindle or axle 21 passing through said actuating wheel 20 said actuating wheel being rotatable about axle 21. Axle 21 has one end thereof 21a formed at a substantially right angle to the axis of said axle. (As best shown in FIG. 8). The opposite end of axle 21 is accommodated in a housing guide 22 which is provided with a guide slot (not shown) for accommodating said opposite end of axle 21. It should be noted that the guide slot allows the end of axle 21 to move in a plane normal to the face of semicircular portion 10b but prohibits movement of axle 21 in a plane parallel to the face of said semicircular portion. The formed end 21a of axle 21 is in slideable engagement with aperture 23 which is situated at the center of the diameter of said semicircular portion 10b.

The second clutch means further includes a retraction and maintenance means 24 provided with a magnet 24a which performs the same function as did magnet 17a of retraction and maintenance means 17 included in the first mentioned clutch means. Also, as was the case in the first clutch means, a contact bar 25 is carried by axle 21 which is similar in structure and function as contact bar 18 associated with axle 21. Thus, upon the application of a normal force to contact bar 25, axle 21 is disengaged from the magnetic force of magnet 24a and axle 21 is thereby displaced normally from the face of semicircular portion 10b thereby causing the formed end 21a of axle 21 to pass through aperture 23 and engage drawing media, while actuating wheel 20 concurrently passes through opening 26 in straight edge portion 10a and likewise engages the drawing media.

Thus the application of an additional force parallel to the plane of the drawing media while maintaining a normal force on contact bar 25, will cause the instrument to rotate in a circular path as indicated by Arrow B in FIG. 1. Upon the release of said normal force upon contact bar 25, magnet 24 will retract axle 21, thereby disengaging the formed end 21a thereof and actuating wheel 20 from the drawing media. To insure a positive engagement of formed end portion 21a of axle 21 with the drawing media, a sharp point 21b may be located at the extreme end of said formed end so that said end is lightly embedded in the drawing media.

Although a disengagement of actuating wheels 14 and 20 from the drawing media would allow the instrument of the instant invention to lay flat on said drawing media without movement in any direction, in order to positively prohibit movement of the drawing instrument in any direction a braking effect is realized by simultaneously applying a normal force to contact bar 18 and to contact bar 25 so that actuating wheels 14 and 20 simultaneously engage the drawing media. This is due to the fact that the axis of axle 21 is not parallel to the axis of axle 15 so that rotation of the wheels about their respective axis is prohibited.

It should be noted that the upper right-hand quadrant of semicircular position 10b is omitted. Further, the ad-

ja⁵cent upper left-hand quadrant of said semicircular portion 10b has a cut-out portion so that the circumference of the modified quadrant is concentric with the outer circumference of semicircular portion 10b. Of course, the measuring indicia 12 is consistent not only through the original quadrant and the modified quadrant, but continues across the face of the straight edge portion 10a so that in effect, three quadrants of the circle are represented.

The measuring indicia 12 of semicircular portion of 10b, as is the case at measuring indicia 11 of straight edge portion 10a, are predetermined to read measured distances, angles and the like, or may be utilized primarily for reference points.

The off-set circumferential edge of the upper left-hand quadrant and lower left-hand quadrant of semicircular portion 10b both intersect at shoulder 27. (As best seen in FIG. 1). Diametrically across from shoulder 27, by omission of the right-hand quadrant of the semicircular portion 10b, a second shoulder 28 is formed which is situated in the same plane as shoulder 27.

Shoulders 27 and 28, and leading edge 29 of straight edge portion 10a all lay in the same plane which passes slightly below, and parallel to the true diameter passing through the center of semicircular position 10b so that shoulder 27 and 28 and the forward edge 29 of straight edge position 10a are slightly off-set below a said true diameter.

The off-set shoulders 27, 28 of semicircular position 10b and forward edge 29 of straight edge portion 10a provides an automatic alignment of the marking instrument along the forward edge 29 of straight edge portion 10a and shoulders 27 and 28 with the true diameter of the semicircular portion 10b. Thus a true reference line may be easily established to assist the draftsman in the preparation of his drawings and the like.

While one embodiment of the invention has been described, it is understood that the particular embodiment of the invention herein disclosed is for illustrative purposes only and the various changes may be made therein without departure from the principles of the invention.

I claim:

1. An integral, mobile drafting instrument, comprising:

a body, said body having a straight edge portion and a circular portion, said body having a plurality of openings passing therethrough, a first clutch means carried by said body for providing forward motion to said body relative to a drawing media or the like upon the application of an extraneous force thereto, said first clutch means being comprised of first rotatable contact means having spindle means secured thereto, means for accepting an extraneous force carried by said spindle means for lowering said rotatable contact means through said openings into an operative position, means for retracting said first rotatable contact means from an operative to an inoperative position by withdrawing from said openings, means for preventing lateral movement of said first rotatable contact means due to transient forces, and a second clutch means carried by said body for providing rotational motion to said body relative to a drawing media or the like upon the application of an extraneous force thereto, said second clutch

means being comprised of a second rotatable contact means having spindle means rotatably secured thereto, said second rotatable means situated in the same plane as said first rotatable contact means, the axis of rotation of said second rotatable contact means being angled with respect to the axis of rotation of said first rotatable contact means, said spindle means having one end thereof formed normally to the axis of said spindle means so as to be slideably accommodated in an opening passing through the body, said opening being located at the radial center of the circular portion of the body, means for accepting an extraneous force carried by said spindle means for lowering said second rotatable contact means through at least one of said openings into an operative position, means for retracting said second rotatable contact means from an operative to an inoperative position by withdrawing from at least one of said openings, engagement means for accommodation of the end of said spindle means opposite said formed end for preventing lateral movement of said spindle means relative to the body yet allowing movement in a plane normal to said body.

2. An integral, mobile drafting instrument as described in claim 1 wherein said first rotatable contact means are wheel means and said spindle means passes through the center thereof.

3. An integral, mobile drafting instrument as described in claim 2 wherein said wheel means are comprised of a plurality of friction wheels, said friction wheel being associated with at least a plurality of said openings passing through the body and being of lesser dimension that the openings so as to be able to pass through said openings.

4. An integral, mobile drafting instrument as described in claim 2 wherein said means for accepting an extraneous force in a sleeve means positioned about said spindle means in loose slideable association therewith.

5. An integral, mobile drafting instrument as described in claim 2 wherein said means for retracting said first rotatable contact means are magnetic means positioned in spatial relationship above said body.

6. An integral, mobile drafting instrument as described in claim 5 wherein said spindle means are composed at least in part of a ferrous compound.

7. An integral, mobile drafting instrument as described in claim 2 wherein said means for preventing lateral movement of said first rotatable contact means are a plurality of abutment means positioned at both ends of said spindle means to engage said ends of the spindle means so as to prevent lateral movement thereof, and resilient spring means situated between one of said abutment means and said first rotatable contact means.

8. An integral, mobile drafting instrument as described in claim 2 wherein said second rotatable contact means are wheel means and said spindle means passes through the center thereof.

9. An integral, mobile drafting instrument as described in claim 8 wherein said wheel means are comprised of a friction wheel, said friction wheel being associated with at least one of said openings passing through the body and being of smaller dimension than the openings so as to be able to pass through said openings.

10. An integral, mobile drafting instrument as described in claim 8 wherein said means for accepting an extraneous force is a sleeve means positioned about said spindle means in loose slideable association therewith.

11. An integral, mobile drafting instrument as described in claim 8 wherein said means for retracting said rotatable contact means are magnetic means positioned in spatial relationship above the body.

12. An integral, mobile drafting instrument as described in claim 11 wherein said spindle means are composed at least in part of a ferrous compound.

13. An integral, mobile drafting instrument as described in claim 2 wherein said engagement means for accommodation of one end of the spindle means is an abutment means secured to the body, said abutment having an elongated indent therein extending normal to the plane of the body for accommodating the end of the spindle opposite the formed end thereof.

14. An integral, mobile drafting instrument as described in claim 1 wherein said straight edge portion and said circular portion are provided with predetermined marking indicia about the edges thereof.

15. In an integral, mobile drafting instrument, a means for drawing curved lines and predetermined angles, comprising:

a body, said body having a straight edge portion and a circular portion, said body having plurality of openings passing therethrough;
rotatable contact means carried by said body, said 30 rotatable contact means having spindle means rotatably secured thereto, said spindle means having one end thereof formed normally to the axis of said spindle means so as to be slideably accommodated in an opening passing through the body, said opening being located at the radial center of said circular portion;

means for accepting an extraneous force carried by said spindle means for lowering said rotatable contact means into an operative position through 40 at least one of said openings;

means for retracting said rotatable contact means from an operative to an inoperative position by withdrawing from at least one of said openings; and

engagement means for accommodation of one end of said spindle means for preventing lateral movement of said spindle means relative to said body yet allowing movement in a plane normal to said body whereby when said rotatable contact means are in an operative position they serve as means to move said drafting instrument over the drawing media.

16. In an integral, mobile drafting instrument as described in claim 15 wherein said rotatable contact means are wheel means comprised of a friction wheel being associated with at least one of said openings passing through the body and being of smaller dimension than the openings so as to be able to pass through said openings, and said spindle means passes through the center thereof.

17. In an integral, mobile drafting instrument as described in claim 15 wherein said means for accepting an extraneous force is a sleeve means positioned about

said spindle means in loose slideable association therewith.

18. In an integral, mobile drafting instrument as described in claim 15 wherein said means for retracting 5 said rotatable contact means are magnetic means positioned in spatial relationship above the body.

19. In an integral, mobile drafting instrument as described in claim 18 wherein said spindle means are composed at least in part of a ferrous compound.

20. In an integral, mobile drafting instrument as described in claim 15 wherein said engagement means for accommodation of one end of the spindle means is an abutment means secured to the body, said abutment having an elongated indent therein extending normal to the plane of the body for accommodating the end of the spindle opposite the formed end thereof.

21. In an integral, mobile drafting instrument, a means for drawing straight lines, comprising:

a body, said body having a straight edge portion provided with a plurality of openings passing therethrough;

rotatable contact means attached to said body, said rotatable contact means having spindle means secured thereto;

means for accepting an extraneous force carried by said spindle means for lowering said rotatable contact means into an operative position wherein said contact means pass through said openings;

means for retracting said rotatable contact means from an operative to an inoperative position by withdrawing said rotatable contact means from said openings, said means for retracting said rotatable contact means being magnetic means positioned in spatial relationship above said body; and

means for preventing lateral movement of said rotatable contact means.

22. In an integral, mobile drafting instrument, as described in claim 21 wherein said rotatable contact means are wheel means comprised of a plurality of friction wheels, said friction wheel being associated with at least a plurality of said openings passing through the body and being of lesser dimension than the openings so as to be able to pass through said openings, and said spindle means passes through the center thereof.

23. In an integral, mobile drafting instrument as described in claim 21 wherein said means for accepting an extraneous force is a sleeve means positioned about said spindle means in loose slideable association therewith.

24. In an integral, mobile drafting instrument as described in claim 21 wherein said spindle means are composed at least in part of a ferrous compound.

25. In an integral, mobile drafting instrument as described in claim 21 wherein said means for preventing lateral movement of said rotatable contact means are a plurality of abutment means positioned at both ends of said spindle means to engage said ends of the spindle means so as to prevent lateral movement thereof, and resilient spring means situated between one of the said abutment means and said rotatable contact means.
